DIE ROLLING BAR STOP

Herbert G. R. Bennett, Duquesne, Pa.

Application June 13, 1936, Serial No. 85,153

7 Claims. (Cl. 80—26)

The present invention relates to a die rolling bar stop adapted to be normally positioned between the die rolls to prevent a bar from entering between the rolls until the rolls are in proper rolling position and includes means for automatically withdrawing the stop from its position between the rolls to permit the bar to pass through the rolls for treatment.

Other objects and advantages will become apparent as the description proceeds in which,

Figure 1 is a side elevation of the stop bar mechanism in a position between the die rolls.

Figure 2 is an end elevation partly in section of the assembly showing the relative positions of the clutches and cam, and

Figure 3 is a diagrammatic showing of the circuit for effecting operations of the various movements of the stop mechanism.

In the drawings, 2 and 3 represent superimposed die rolls driven by any conventional mechanism operated by a motor "C" in the direction indicated on the drawings by the arrows. These rolls, which can contain any practical number of units, are adapted to rotate continuously in one direction, but in case of an emergency may be reversed in rotation by reversing the direction of rotation of the motor. There is conveniently located at the rear of the rolls 2 and 3, a shaft 4 suitably secured to the frame of the rolling mill and suspended therefrom and keyed thereto is a stop rod 5 depending downwardly from the shaft, behind the rolls, and provided with a lateral horizontal extension 6 projecting toward the rolls 2 and 3 which prevents the bar 7, normally fed by the roll table 8 to the rolls for treatment, from entering these rolls until they are in correct operating position. Attached to the upper roll 2 is a cam member or plate 9 provided with cam surfaces or lobes 13 arranged to operate a limit switch 10 when the rolls reach their proper position. In case a number of roll units are provided, the cam would have a similar number of lobes.

Mounted on a suitable support, and concentric with the shaft 4, is a magnetic holding clutch 12, which magnetically locks into position, the stop rod 5 when the clutch 12 is electrically energized. A sleeve 14 is mounted on the shaft 4 and permits rotation of the shaft within the sleeve, while mounted on the sleeve 14, and revolving thereon, is a magnetic rotating clutch 15, continuously operated by an electric motor 16. Secured on one end of the shaft 4 is a cam member 17 operating a limit switch 18 adapted to energize the rotating clutch 15 for moving the stop rod 5 and

lateral extension 6 away from its position between the rolls and out of the path of travel of the bar 7, as shown in dotted lines in Figure 1. This limit switch is provided with contacts for making electrical connection to contacts 30—30 5 and 34—35 to be hereinafter described.

During the movement of stop rod 5 to its position shown in dotted lines in Figure 1, the cam 17 operates the limit switch 18 for de-energizing the rotating clutch 15 and finally energizing the holding clutch 12 so as to maintain the stop rod 5 in its dotted line position out of contact with the bar 7 and away from its position between the rolls. In order to prevent the holding clutch 12 and rotating clutch 15 from being energized simultaneously, which would cause damage to the equipment, the clutches 12 and 15 are electrically controlled so that both cannot be energized at the same time.

It is possible to use different types of operating circuits to control the various clutch operations under the present invention. However, an example of a specific circuit which may be adopted and used to control the various operations of the clutches and switches is shown diagrammatically in Figure 3, and the operation is as follows.

Assuming that a bar 7 has been rolled and the main switch 19 for supplying a source of current to the motor is closed for operating the motor "C" whereby the rolls 2 and 3 are rotating in the direction indicated by the arrows in Figure 1, the motor 16 being in operation and rotating the magnetic clutch 15, the subsequent operations follow: holding clutch 12 is energized to maintain the stop rod 5 up in the dotted line position shown in Figure 1, which is out of its position between the rolls 2 and 3 and after a subsequent bar 7 approaches the die rolls 2 and 3, either lobe 13 on cam 9 may operate the limit switch 10 to open its closed contact; thus, de-energizing the coil 20 and opening the normally closed contacts 22—23, thereby de-energizing the holding clutch 12 and permitting the stop rod 5 to return, by gravity, into a position between the rolls 2 and 3.

As the lobe 13 of the cam 9 moves downwardly away from the switch 10, the switch is returned to its original closed position to close a circuit from line P through line 53, switch 10 and normally closed contacts 30—31, line 54, coil 20, line 55 to line N, thereby energizing coil 20 and closing contacts 22—23, which, in turn, complete a circuit from line P, through line 50, contacts 22—23, line 51, coil of clutch 12, and line 52 to line N. This last named circuit energizes the

coil of clutch 12 and locks the stop-rod 5 in position between the rolls 2 and 3.

As the bar 7 approaches the rolls, it cannot enter due to the stop-rod 5 being positioned between the rolls in a locked position. The rollers on table 8 continue to rotate until the die-rolls 2 and 3 pass through a half revolution and one lobe 13 of the cam 9 again operates the limit switch 10, opening the circuit from line P through lines 53 and 54 to coil 20, thus de-energizing this coil and permitting contacts 22 and 23 to open and break the circuit from line P through line 50, contacts 22—23, and line 51 to the coil of clutch 12 whereby the clutch 12 is de-energized and the rod 5 released, which, due to its mounting, remains in position between the rolls until the bar 7 moves into a position between the rolls 2 and 3 and comes in contact with the lateral extension 6 of the stop member, and pushes it rearwardly in the direction of its dotted line position shown in Figure 1. The stop-rod 5 being moved by the bar 7, rotates the shaft 4 through a small arc and, in so doing, rotates the cam 17 to cause its cam face 60 to engage the operating plunger 61 of the switch 18, thus closing contacts 70 and 71 of the switch 18 and making a circuit from line P through line 56, coil 26, line 57 to line N, thereby energizing coil 26 and closing contacts 24—25 to complete a circuit from line P through line 58, contacts 24—25, line 59, coil of the clutch 15, line 80 to line N. This last named circuit energizes the coil of clutch 15 which, through its connection with the shaft 4, swings the stop-rod 5 out of its position from between the rolls and the line of travel of the bar 7, thereby permitting the bar 7 to pass between the rolls 2 and 3 for treatment, which rolls will have revolved sufficiently to permit the plunger 61 to move outwardly and open the contacts 70 and 71 of the switch 18 which de-energizes the coil 26 and permits contacts 24—25 to open, thereby de-energizing the coil of clutch 15 which releases the stop-rod 5.

When the bar 7 moves into a position between the rolls 2 and 3 and cam face 60 of the cam 17 engages plunger 61 of switch 18 to close the contacts 70—71 as described above, the cam face 62 simultaneously releases the plunger 63 of the switch 18 so as to open the contacts 30—31 of the switch 18 so as to prevent the coil 20 from being repeatedly energized by the switch 10 while the bar 7 is passing through the rolls 2 and 3.

Also simultaneously with the closing of contacts 70—71 and the opening of contacts 30—31, the cam face 64 of the cam 17 engages the plunger 65 of the switch 18 to close contacts 85—86 of the switch 18 so as to close the line 81.

Closing of the contacts 70—71 simultaneously with the making of a circuit to the coil 26 also makes a circuit from line P through line 56, line 81 and coil of timing relay 33 to line 82, through contacts 34—35, line 83 to line N, so as to energize the adjustable timing relay 33, and close contacts 40—41, thus energizing the holding clutch 12 during the entire time the bar 7 is passing under the stop 5. This relay 33 is set to close after a predetermined time interval so that the holding clutch 12 is energized through a normally closed switch 42, operated by the coil 20, thereby holding the stop-rod 5 locked in a position out of line with the rolls. This condition will continue either until one of the lobes 13 of the cam 9 finishes passing by the switch 10 for closing the circuit to the coil 20 and energizing the holding clutch 12 through contacts 22—23

and opening the previously energized circuit by opening the main contact switch 42 and the contacts 34—35, thus breaking the circuit to the adjustable time relay 33, or until the limit switch 10 is opened by the following lobe 13 on cam 9 which would release the stop-rod 5 and permit it to move into a position between the rolls 2 and 3.

This relay 33 is set to close after a predetermined time interval so that the holding clutch 12 is energized through a normally closed switch 42, thereby holding the stop rod 5 locked in a position out of line with the rolls. This condition will continue either until one of the lobes 13 of cam 9 finishes passing by the switch 10 for closing the circuit to coil 20 and energizing the holding clutch 12 through contacts 22—23 and opening the previous energized circuit by opening the main contact switch 42 and the contacts 34—35; thus breaking the circuit to the adjustable time relay 33 or until the limit switch 10 is opened by the following lobe 13 on cam 9 which would release the stop rod 5 and permit it to move into a position between the rolls 2 and 3.

While I have shown and described one specific embodiment of my invention, it will be understood that I do not wish to be limited exactly thereto, since various modifications may be made without departing from the scope of my invention as defined by the following claims.

I claim:

1. In combination with a bar rolling machine including bar feeding means and die rollers, a stop adapted to be positioned between said rollers to prevent the material from entering between the rollers until said rollers are in operating position, means adapted to lock said stop in position between said rollers, means adapted to withdraw said stop from its position between said rollers and means operated by the withdrawal of said stop adapted to hold said stop in a withdrawn elevated position.

2. In combination with the bar rolling machine including bar feeding means and die rollers, a stop adapted to be positioned between said rollers to prevent the material from entering between the rollers until said rollers are in operating position, means adapted to lock said stop in position between said rollers, means adapted to withdraw said stop from its position between said rollers and time controlled means adapted to release said stop from its withdrawn position to permit said stop to gravitate to a position between said rollers.

3. In combination with a bar rolling machine including bar feeding means and die rollers, a stop adapted to prevent the material from entering between the rolls until said rolls are in operating position, means adapted to withdraw said stop from its position between said rolls and means operated by the withdrawal of said stop from its position between the rolls to energize a clutch for holding said stop in its withdrawn position.

4. In combination with a bar rolling machine including bar feeding means and die rollers, a shaft, means for rotating said shaft, a stop mounted on said shaft, a holding clutch on said shaft, a rotating clutch on said shaft, means for operating said clutches and means adapted to prevent energizing said holding clutch and rotating clutch simultaneously.

5. In combination with a bar rolling machine including bar feeding means and die rollers, a stop for said material positioned between the

rolls, means adapted to withdraw said stop from between said rolls, means for returning said stop from its withdrawn position to a position between said rolls, means on one of said rolls for operating said last named means, and means operated 5 by the return of said stop to its position between the rolls to lock said stop in position.

6. In combination with a bar rolling machine including bar feeding means and die rollers, a stop for said material positioned between the 10 rolls, means adapted to withdraw the stop from between the rolls and means adapted to hold said stop in a locked position out of line of the path

of the material and means on one of said rolls for releasing said stop holding means.

7. A die rolling bar stop comprising a member adapted to be positioned between superimposed die rolls and provided with an upwardly extending arm, said arm secured to a shaft and rotatable therewith, a clutch adapted to move said stop from between said rolls, a clutch adapted to maintain said stop in withdrawn position and means on said shaft adapted to control the operation of said clutches. 5 10
